UNITED STATES PATENT OFFICE

KONOSUKE TSUCHIYA, OF SAUSALITO, CALIFORNIA

CONTAINER AND PROCESS OF MAKING SAME

Application filed November 29, 1930. Serial No. 499,024.

This invention relates to containers and process for making same, and relates more particularly to bottles generally of the type described in my United States Letters Patent No. 1,776,458, dated September 23, 1930, liquid container, on which application for reissue patent was filed by me on November 8, 1930, Serial No. 494,437, which are made of fiber board or chip board and usually 10 treated with a water proofing substance, such as paraffin.

This type of container is especially useful in the dairy industry, wherein the invention may take the form of a bottle, but the invention 15 may be used in numerous other types of containers, although the description herein is, for concrete exemplification of one form of the invention, described in respect of bottles for use in the dairy industry.

20 Objects of the invention are to provide a container having a bottom which may be inserted in or removed from the container body, to provide a bottom closure which by inherent resilience and by a crowned top will increase 25 the tightness of sealing by the weight of bottle contents; to provide a container which has a tight seal between such a bottom and the container wall; to provide a combination of a container and a bottom, both of which may 30 respectively be closely nested for shipment, and provide reinforcement substantially throughout their entire surfaces, so as to avoid injury which would prevent them from forming perfectly fitting parts when associated 35 together; to provide a container in which both bottom and body may be shipped in nested form by the manufacturer, and which may be operatively associated by the purchaser by a simple operation, so as to form a 40 tight grooved seal between bottom and body; and to provide a process whereby the foregoing objects may be accomplished.

In my above mentioned co-pending application, I have shown a container in which an 45 inwardly opening groove was formed in a body adjacent its lower edge, and a complementary portion was formed in a crowned and skirted bottom closure, and when the bottom closure was manually or mechanically 50 placed in the bottom opening of the con-

tainer, the complementary portion of the bottom found a seat in the inwardly opening groove. I am also aware of prior patents which disclose various types of containers having bottoms which may be inserted in the 55 container, some of them providing flat discs engaging a groove, others providing flat skirted discs and others providing crowned discs without skirt or body groove. None of these patents describe or illustrate the device of this invention, nor accomplish its 60 purpose, nor are they adaptable to the process described and claimed herein. An object therefore is to simplify the structure of such containers, provide for nesting of all parts 65 and thereby the protection of edges from mutilation in shipment, and provide the parts so that they may be operatively assembled by a user after receipt of the separate parts, so as to form a container leak-proof to the 70 same extent as though the parts were assembled by groove engagement at the factory.

With the above mentioned and other objects in view, the invention consists in the novel construction and combination of parts 75 hereinafter described, illustrated in the accompanying drawing and pointed out in the claims hereto appended; it being understood that various changes in the form, proportion, size and minor details of construction within 80 the scope of the claims may be resorted to without departing from the spirit or sacrificing any of the advantages of the invention.

To more clearly comprehend the invention, reference is directed to the accompanying 85 drawing, wherein—

Fig. 1 is a vertical transverse section of a series of nested container bodies with a spaced top and a spaced bottom closure.

Fig. 2 is a broken view of a vertical transverse sectioned top portion of a container body, showing a well known disc cap.

Fig. 3 is a vertical transverse section of a container body showing top and bottom in place and grooved with the body.

Fig. 4 is a side elevation of bottom closure prior to insertion and crimping of engaging groove in container body.

Fig. 5 is a vertical transverse section of a modification of Fig. 3, showing a plurality of 100

interengaging grooves between body wall and skirted closure.

Fig. 6 is a vertical transverse section of a modification of Fig. 3, showing an inwardly turned interengaging groove between body wall and skirted closure.

Fig. 7 is a plan view of modification of top plane of closure member, showing radial grooves instead of the crowned plane of Fig. 4.

Fig. 8 is a plan view of another modification of top plane of closure member, showing concentric circular grooves in place of the crowned plane of Fig. 4.

Referring to the drawing, wherein like characters of reference designate corresponding parts, A indicates generally a tubular body having side walls 1, which are preferably made of fiber board or what is known in the trade as chip board, which material has sufficient rigidity to normally hold its formed shape, but which is slightly flexible, and slightly deformable, for purposes hereinafter set forth. The body may assume any suitable tubular form, but since the dairy industry prefers a bottle in which cream may rise to the top of milk contents, it is preferred that the body generally follow in principle the lines of the ordinary dairy milk bottle, and I have therefore illustrated a container body outwardly flaring from top to bottom, forming substantially a truncated tubular conical shape, which nest in a well known manner, as shown in Fig. 1.

The bottle as originally formed is provided with an open top 2 and an open bottom 3. The top 2 is closed by a suitable closure means, and this may assume the form of the well known flat disc 4, which is made of proper size to snugly fit the face of a shoulder 5 on the inner face of the bottle neck recessed from the top opening. This form of closure is old and requires a forming of the bottle neck to receive it, and I do not claim anything new therein. The bottle top may also be closed with the same type of closure member which is herein described more fully relative to the bottom closure member.

A bottom closure member 6, circular in plan, is provided which comprises a disc 7, having its top plane provided with greater surface area than the geometric plane in which it lies and preferably crowned from edge to edge, as at 8, and having a skirt 9 formed integrally therewith and depending from the peripheral edge of the disc. The disc is preferably made of heavy weight manila paper, sometimes called stock or card-board, but in any event to have a sufficient degree of resilience and flexibility to rebound against the walls of the container when inserted therein, due to pressure of the crowned plane portion 8 of the disc 7, which seeks its pre-formed shape and presses the side walls or skirted portion 9 radially outwardly.

It will be noted that in the preferred form, the disc 7 is similar in diameter to the inner diameter of the body 1 at that point of the body removed from the peripheral bottom body edge approximately the distance of the vertical height of the skirt of the bottom closure. This is so that when the bottom closure 6 has been pressed into the open bottom 3 to the depth of the skirt 9, the disc 7 will snugly fit the side walls of the body, and also for the purpose that the plane of the bottom closure 6 will find its proper seat merely by dropping the closure loosely into the open bottom of the body and then tapping the body upon any even plane surface, whereby the lower peripheral edges of the skirt and body are pressed into lateral transverse alignment.

In forming the skirt 9, it is desirable that it should be flared outwardly from the periphery of the plane 7 to a small extent, so that the circumferential bottom edge conforms to a diameter greater than the peripheral edge of the bottom opening 3 of the body 1, preferably about one-sixteenth of an inch, so that there will be sufficient frictional contact between the inner face of the body wall and the outer face of the skirt, to provide a snug fit for the temporary holding of the closure in place. This excess of diameter is absorbed by the flexibility of the material of the closure member when placed within the body, under pressure. It is self-evident that in manufacturing the closures the skirt portion would be made to generally correspond with the form of the body at its open end portion, but my invention contemplates the improvement of so forming the bottom closure that it will closely nest for shipment; will exert a frictional pressure against the inner body walls by reason of a depending skirt which receives radial resilience from a crowned plane of the bottom closure, and which when an interengaging groove is formed in the skirt and body wall after the closure has been inserted in the body opening, will allow for radial expansion of the skirt and plane of the closure to permit formation of the groove without fracture of the closure member; at the same time maintaining the closure member in spaced relation to the transverse plane of the bottom edge of the container, and it is the combination of these improvements wherein my invention lies.

When the bottom closure member 6 has been placed within the bottom opening 3 so that the inner body wall and the skirt wall are in frictional contact, one or more interengaging grooves 10 are formed simultaneously in and circumferential of the two contacting walls. The advantage of forming the grooves after the placement of the closure member is that no matter how carefully the body members and closure members are made, if the grooves are placed therein independently before assembly, they will not always fit

to form a leak-proof joint. This is sometimes caused by lack of mathematical precision in forming dies, sometimes by atmospheric conditions of dampness or dryness, sometimes because (with the grooves pre-formed) the respective parts do not nest perfectly in reinforced contact and the grooves or edges become deformed in shipment or in handling. The forming of the groove after juxtapositioning of the body and closure may be accomplished by any suitable die and preferably by suitably shaped complementary convex and concave die wheels on any suitable revolving turret.

15 It is to be understood that any suitable material may be employed for forming the container body and closure member, and that if a porous paper stock is used, and the container is to be used for liquid, the stack 20 should be treated with a water-proofing substance, such as paraffin which is well known in the art.

The top opening 2 of the container may be closed similarly with the bottom opening, 25 but if the container is formed as a tubular truncated cone throughout its length, the top closure 11 is provided with a plane 12 which is of a diameter substantially equal to the diameter of the upper opening 2, which 30 causes the upper closure 11 to be readily seated within the upper conical portion of the body and temporarily maintained thereat by the radially inward pressure of the skirt 13 by the container walls, as indicated by dotted 35 lines Fig. 1, and as shown in Fig. 2. When the groove 14 is simultaneously formed in the juxtaposed closure and body wall, the resilient expansibility of the plane 12 will permit the skirt 13 to be drawn into the 40 groove of the body without fracture and forming a tight leak-proof joint similarly as with the bottom closure above described.

The simultaneously made grooves 10 and 14 may be formed radially outward as in Fig. 45 3 or radially inward as in Fig. 6, and may be one or more in number as desired.

In Fig. 7 and Fig. 8 are shown, in plan, modifications of the plane 8 of the closure members, in Fig. 7 consisting of radial 50 grooves which expand or flatten concentrically, and in Fig. 8 concentric grooves which expand or flatten radially, to provide a resiliency and expansibility to the skirt when the groove is formed in the skirt of the closure 55 member.

Having thus described my invention, what I claim and desire to secure the Letters Patent is:—

60 1. The method of forming a container consisting of the steps of assembling in frictional contact and in overlying planes the skirt of an arcuately crowned closure member having a skirt flared radially outwardly and depending from the periphery of the arcuately crowned portion, and thereafter forming

ing an interengaging groove simultaneously in the said skirt and said container wall.

2. The method of manufacturing a container, consisting of the steps of forming a tubular open-ended body, and separately forming an arcuately crowned saucer-like closure member so that the radially outward peripheral portion of the closure member forms a skirt depending radially outward from the arcuately crowned portion thereof, assembling in overlying planes the skirt and the open-ended portion of the tubular body and thereafter forming an interengaging groove simultaneously in said skirt and the tubular body.

70 3. The method of manufacturing a container, consisting of the steps of forming a tubular open-ended body and separately forming a closure member with a top plane having greater surface area than the geometric plane in which it lies and a skirt flared radially outward and depending from the periphery of the top plane, assembling in overlying planes the skirt and the open-ended portion of the tubular body, and thereafter forming an interengaging groove simultaneously in said skirt and the tubular body.

75 4. A device of the character described, comprising a tubular body having an open end, and a closure member of flexible material adapted to lie within said open end, said closure member having a top plane of greater surface area than the area of the geometric plane in which it lies and having a skirt depending and extending radially outward from the peripheral portion of said top plane, said body and said skirt having provided therein interengaging grooves.

80 In testimony whereof I have affixed my signature.
